SKIMMING LADLE

Lucien Novion, Honolulu, Territory of Hawaii,
assignor of one-half to Olaf Oswald, Honolulu,
Territory of Hawaii

Application December 20, 1948, Serial No. 66,313

3 Claims. (Cl. 210—51)

1

This invention relates to a skimming ladle employed, for example, in connection with dispensing soup.

The body of soup in the cooking kettle is usually overlain by a layer of molten fat which it is not desirable to serve with the soup.

The present invention provides a skimming ladle by means of which the fat may be separated from the soup. The fat is usually conserved by pouring it into a collecting vessel, permitting it to solidify, and accumulating it from day to day until a sufficient quantity has been obtained to constitute a salable unit. The presence of soup in the fat is undesirable, since the soup spoils more readily than the fat and contaminates the fat. Therefore, the purpose of the present invention is slanted toward producing a soup free fat.

One of the objects of the invention is to provide a skimming ladle having a partition which partially occludes the open top of the ladle, so constructed and arranged as to act as a dam when the ladle is tilted for holding back the heavier liquid, and permitting the overflow of the fat.

Another object of the invention is to provide a ladle as described, in which the partition is located a short distance below the plane of the open end of the ladle so that should a small amount of the soup flow over the dam through over tilting of the ladle, it will be retained by the portion of the rim of the ladle above said partition, acting as a rifle.

Other objects of the invention will appear as the following description of a preferred and practical embodiment thereof proceeds.

In the drawing which forms a part of the specification, and throughout the several figures of which the same reference characters have been used to denote identical parts:

Figure 1 is a side elevation of the ladle;

Figure 2 is a top plan view;

Figure 3 is a vertical section in a plane parallel to the direction of tilt of the ladle, the latter being shown in level position with respect to the liquid in the cooking kettle;

Figure 4 is a vertical section in a plane parallel to the direction of tilt of the ladle, the latter being tilted in the direction to discharge the fat.

Referring now in detail to the drawing, the ladle 1, as shown, comprises a bowl 2, having the shape of a section of a hollow sphere, the free edge 3 lying in a single plane. A handle 4 is attached to the bowl 2, perpendicular to the plane

of the edge 3 and has an outwardly turned finger-hold 5 at its upper end.

A planiform partition 6 is secured within the bowl 2 in a plane parallel to the plane of the edge 3 and slightly below said edge. Said partition is the segment of a circle having its acute edge secured in fluid tight manner to the rim of the bowl. In the illustrated embodiment, the free edge 7 is rectilinear, coinciding with the diameter of the bowl in the plane of the partition and perpendicular to the handle 4.

In the employment of this ladle one cannot, of course, expect all users to follow a stereotype technique in using it to obtain the desired result. 15 The preferred way would be to immerse the ladle in the liquid body to the level position approximately as shown in Figure 3, so as to dip a serving of soup with incidentally some supernatant fat. The ladle is then removed from the body of liquid. Then it is tilted to the position shown in Figure 4 and the fat discharged into the collecting vessel, not shown. The rectilinear edge 7 of the partition 6 serves as a guide to the eye in keeping the ladle level in a front to back direction so as to accomplish even skimming of the fat from the soup in the ladle. When the lower level 20 b of the fat (Figure 4) reaches the edge 7 of the partition, it may be that a little soup will run over said edge before the operator has time to 25 check the flow by tilting up the ladle. This soup is caught by the part 9 of the rim, which projects above the partition 6 and does not spill over into the fat collecting vessel.

The ladle is then tilted in the opposite direction, dispensing the substantially fat freed soup into a suitable container.

While the spherical shape of the bowl of the ladle is optimum, in creating minimum turbulence when it is immersed in the body of liquid in the kettle 8, the invention is not limited to a bowl of this shape, and while the invention has been disclosed specifically in its relation to the dispensing of soup, it is obvious that it is equally useful in separating any relatively light liquid from a relatively heavy liquid, when it is desired that the light liquid, after separation, shall not be contaminated with small amounts of the heavy liquid.

50 What I claim as my invention is:

1. Skimming ladle comprising a bowl having a mouth-defining free edge lying in a single plane, a flat partition closing part of the mouth of said bowl, said partition being below the plane 55 of said mouth-defining edge and parallel there-

to, having a peripheral edge coinciding with the adjacent side of said bowl through a substantial perimetrical extent of said side making a fluid tight joint therewith, and having rectilinear free edge extending across said bowl bridging the ends of said joint, said ladle including a handle secured to said bowl for tilting said bowl.

2. Skimming ladle comprising a bowl of spherical curvature having a free edge lying in a single plane, a flat partition within said bowl slightly below said free edge lying in a plane parallel to the plane of said free edge, said partition having the shape of the segment of a circle, with its arcuate edge making a fluid tight joint with said bowl and its chord edge extending across said bowl, and a handle secured to said bowl at one end of said chord edge, extending perpendicularly to the plane of said free edge.

3. Skimming ladle comprising a bowl having a mouth-defining free edge lying in a single plane, a flat partition closing part of the mouth of said bowl, said partition being below the plane of said mouth defining edge and parallel thereto, having a peripheral edge coinciding with the

adjacent side of said bowl throughout a substantial perimetrical extent of said side making a fluid tight joint therewith, and having a rectilinear free edge extending across said bowl bridging the ends of said joint, said ladle including a handle secured to said bowl at a point in a medial plane through said bowl parallel to said rectilinear edge and perpendicular to said partition.
